CIGARETTE ROLLING DEVICE

George M. Biner, Los Angeles, Calif., assignor of
one-half to Raymond M. Bailey, Whittier, Calif.

Application March 13, 1945, Serial No. 582,538

3 Claims. (Cl. 131—51)

1

This invention relates to cigarette making devices and has for its primary object to provide a simple, inexpensive and easily operable device for the making of cigarettes in the home and without prior experience.

Another object of the invention is to provide means facilitating the rolling of cigarettes in a sure and competent manner.

Another object of the invention is to provide a novel method for rolling a cigarette without previous experience.

My invention also has for its objects to provide such means that are positive in operation, convenient in use, economical to manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a plan view of a cigarette making device incorporating the invention.

Fig. 2 is a side view thereof.

Fig. 3 is a sectional view as taken on the line 3—3 of Fig. 1, and shown in initial operating condition.

Fig. 4 is an enlarged sectional view, showing an intermediate stage of the cigarette rolling operation.

Fig. 5 is a similar view, showing the final stage of the operation.

In that form of the invention which is illustrated in the drawing, the cigarette rolling device comprises, essentially, a plate member 10 serving as a support and affording means along which a cigarette may be rolled, and a flexible, pliable or substantially pliable band or web 11.

As herein contemplated, the plate member may comprise a platform 15, preferably provided with a rolled edge bead 16 at one end thereof and a rolled edge bead 17 on each lateral edge thereof. In addition to affording a smooth finish to these edges, the platform 15 is strengthened, thereby enabling forming the plate member 10 of relatively thin and light material, such as aluminum and the like.

The end of the plate member opposite the edge 16 may be upwardly folded to provide a wall 18 substantially normal to the platform 15 and then

2

doubled back to provide a wall 19 extending below the platform 15 to provide both a support leg for one end of the platform and a surface upon which one end 20 of the web 11 may be affixed. 5 The other end 21 of said web may be trained about the edge 16, doubled back under the platform 15 and secured thereto. Various means may be employed for securing the web ends 20 and 21, and such means may comprise adhesive, adhesive means, or rivets, tacks or the like.

The web 11 may be made of a suitable material capable of being sharply rolled without deleterious effect. Such a material may be some of the vellum types of paper, skived leather, fabric, cellulose sheet, etc. The width of the web may approximate the length of a cigarette and said web may have a length between its fixed ends somewhat longer than the length of the platform 15, such excess length or slack of the web affording 10 a bight or loop therein 22 for a small cylindrical body, as later apparent.

The plate member 10 is also preferably provided with lateral walls 25 arranged in flanking relation to the lateral edges of the web. Each 15 wall 25 is preferably provided with a seat 26 for resting engagement of an object such as a pencil P, and with downwardly sloping edges 27 extending from said seat 26 to the platform 15 said edges acting as part of the means for guiding the movement of the object whereby the tobacco is 20 rolled into a cigarette.

It will be noted that the plate member 10 is integrally formed, all of the various folds and walls being folded from a single sheet in a manner to provide the light, rigid structure herein contemplated. Also, the platform is supported at an angle between edge 16 and wall 19 to provide more clearance, with respect to a support for the device, for manipulation of object P.

40 In operation, a preferably round object P is inserted into the bight 22 provided in the web 11, and a re-entrant bight 22^a formed in the web, as best seen in Fig. 3, by placing the object P against the seats 26 of the walls 25 and holding the same 45 there. A pocket or trough is thus formed, being defined by the web comprising the bight 22^a and the lateral walls 25. Into this pocket there is placed a suitable quantity of tobacco T which is spreaded uniformly therein. A cigarette paper S may then be placed upon the portion of the web which is resting upon the platform 15 with one edge thereof adjacent to the tobacco T. If desired, at this time the other edge C of the cigarette paper may be moistened.

50 The object P is then moved down in continuous

contact with the sloping edges 27, as shown in Fig. 4, the object P sliding in the web bight 22 as said object engages successive portions of the web. This causes the bight or trough 22^a to roll the tobacco T therein along successive portions of the web, said web unrolling from the bight 22 and rolling into the bight 22^a. As the motion of the object P progresses, the adjacent end of the cigarette paper S is rolled around the tobacco T, and the bight 22^a becomes more sharply curved until the object leaves the edges 27 and slides along the flat part of the web 11. The motion of the object continues until the entire cigarette paper is rolled around the tobacco in the bight 22^a, the present device being made of sufficient length to insure, perhaps, at least two complete revolutions of the rolled cigarette before dropping off the end 16 of the device. Because of the moistened edge e, the cigarette thus rolled will retain its form as can be understood. If desired, the moistening of the cigarette paper may be accomplished after the cigarette is completely formed, it being grasped as it leaves the bight 22^a and moistened in the usual manner.

The device herein may be rested upon a table when in use or may be held in one hand as the other moves the object P along the platform in cigarette rolling motion. It is apparent that in a short time many cigarettes may be rolled without previous experience.

It is to be understood that the sides 17 may be bent upwardly, if it is desired to form the cigarettes more loosely, so that they will draw more easily. Moreover, if it is desired to make cigarettes of smaller diameter, a small cylindrical object that is at least as long as the web 11 is wide, may be inserted where indicated by the circle 33. This will reduce the effective length of the web. Different diameters of object 33 will vary the diameter of the cigarettes.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. A cigarette rolling device comprising, a rigid platform-like member having an end wall and lateral walls adjacent thereto, said end wall extending below the platform to comprise an end support that supports the platform at an upward angle from its opposite end, a web affixed at each end thereof to opposite ends of said platform-like member and of sufficient length to pro-

- vide slack in the web, said slack affording space between the web and the platform for the insertion therebetween of an object adapted to form a bight in said web, said slack in the web also affording a re-entrant bight adjacent to the bight formed by the object, said re-entrant bight and said lateral walls comprising a tobacco receiving trough, and means guiding the movement of the object to cause unrolling of the bight of the web around the object and simultaneously rolling into the other bight successive portions of said web whereby said tobacco is rolled into a cigarette paper disposed upon said successive portions of the web, said latter means comprising edge portions of the lateral walls and portions of said platform, and said edge portions being sloped from a higher point adjacent the end wall to the level of the platform along an intermediate point in the length of said plate member.
2. In a cigarette rolling device an integral plate member comprising, a bead fold along one end edge thereof, a similar bead fold along each lateral edge and extending for substantially the greater length of the plate member, upstanding lateral walls along the remaining length of said plate member, an upstanding end wall adjacent the upstanding lateral walls, and a down-reaching wall formed from the end wall and extending below said plate member.
3. In a cigarette rolling device an integral plate member comprising, a bead fold along one end edge thereof, a similar bead fold along each lateral edge and extending for substantially the greater length of the plate member, upstanding lateral walls along the remaining length of said plate member, an upstanding end wall adjacent the upstanding lateral walls, and a down-reaching wall formed from the end wall and extending below said plate member, said lateral walls each having a sloping edge terminating inwardly of the respective lateral bead fold at a correspondingly intermediate point in the length of the plate.
